UNITED STATES PATENT OFFICE.

EDWIN B. STIMPSON, OF BROOKLYN, NEW YORK, ASSIGNOR TO EDWIN B. STIMPSON COMPANY, OF BROOKLYN, NEW YORK.

RIVET.

Application filed September 28, 1921. Serial No. 503,861.

To all whom it may concern:

Be it known that I, EDWIN B. STIMPSON, a citizen of the United States, residing at Brooklyn, in the county of Kings and State 5 of New York, have invented certain new and useful Improvements in Rivets, of which the following is a specification.

This invention relates to rivets of the sheet metal type and the objects of the invention are to provide a fastening of this character which will be light and strong and in which a minimum amount of material will be used, so that with its other advantages the device will be quite inexpensive.

15 In the accompanying drawing I have illustrated various forms of the invention wherein these objects are accomplished, but do not wish to be understood as limiting the invention to these particular forms.

20 Figure 1 in the drawing referred to is a plan view of the rivet as it appears before the prongs are brought together in their final relation.

Figure 2 is a cross sectional view through 25 the head of the rivet and showing one of the upstanding prongs.

Figure 3 is a sectional view taken on substantially the plane of line 3—3 of Figure 1.

Figure 4 is a plan view of the fastening 30 in its completed form.

Figure 5 is a sectional view on substantially the plane of line 5—5 of Figure 4.

Figure 6 is a side view of a modified 35 form of the rivet in partly completed condition.

Figure 7 is a cross sectional view of the same in its completed form.

Figure 8 is a broken side view of another 40 modification in uncompleted form.

Figure 9 is a cross sectional view of the same as completed.

Figure 10 is a plan of another modification in uncomplete form.

Figure 11 is a cross sectional view of the 45 completed embodiment of the same.

Figure 12 is a cross sectional view of another modification.

50 Figures 13 and 14 are angularly related cross sectional views of a still further modification.

In all forms of the invention there is a domed or arched head 15 formed by cupping the body portion of a sheet metal blank.

Also in the various forms disclosed there 55 are two integral prongs 16, 17 attached at

diametrically opposite points to the skirt or rim of the head.

Another feature in common is that in all the forms disclosed the prongs have straight base portions 18, 19 extending as a bridge 60 across the cavity of the head, the active portions of the prongs projecting from the center of this bridge and the bridge being reinforced in most instances by a strut or struts to prevent it from collapsing into 65 the hollow of the head.

In the form of the invention shown in Figures 1 to 5 the bridge formed by the parts 18, 19 is supported at the center by lugs 20 partially cut out of the material 70 of the base parts 18, 19 and projecting back into engagement with the bottom of the cup (Figure 5).

The active or penetrating portions of the prongs may be pointed as indicated at 21 75 and these parts also may be arched transversely with their concavity to the outside, as indicated at 22, so that when the prongs are bent back to back the convex portions will be in flat engagement as shown 80 in Figure 4.

In making up the fastening in this form, after the blank is cupped, as shown in Figures 1 and 2, the attached tongues which form the prongs are bent on the lines 23, 85 Figure 2, so as to define the base portions 18, 19 and set the points of the prongs at an angle to such base portions, as indicated in dotted lines, Figure 3. It will be noted in Figure 2 that the bend 23 is at substantially the base of the cut-out tongues 20 so that said tongues will swing with the points of the prongs and therefore project inward at a right angle when the bend is made (Figure 3). The bases of the prongs are 90 next bent at 24 at their junction with the rim of the head so as to bring the points or projecting parts of the prongs back to back, with the struts 20 resting on the bottom of the cup, as shown in Figure 5. In 100 this final position it will be seen that the points of the prongs brace each other and that the struts form a direct thrust connection between the penetrating parts of the prongs and the back of the head, the base portions 18 and 19 serving primarily 105 simply as devices for positioning the prongs at the center of the head.

With this construction it will be seen that no metal is lost since the centering portions 110

18, 19 project from the rim of the head straight to the center of the rivet, the struts 20 being taken from an excess of metal in these centralizing base portions.

5 In Figures 6 and 7 I have shown how the strut extending into the back of the hollow head may be eliminated and a somewhat similar bracing effect be obtained by fastening the base portions of the prongs together with integral tongues 25, 26 partially cut from the body portions of the prongs and clinched through the openings afforded by the bending up of these lugs. The fastening of the prongs together in 10 this way, it will be seen, serves to transmit the thrust across the base portions 18, 19 to the rim of the head.

The structure of Figures 8 and 9 is generally similar to that last described, the 20 main distinction being that the prongs are fastened together at their bases by bending lugs 27 at the edges of one of the prongs into notches 28 provided in the edges of the other prong.

25 In Figures 13 and 14, I have shown how this last structure may be modified to provide a thrust transmitting brace by cutting out a thrust lug 20 from between the edges of the base portions of one of the 30 prongs, as in the first form disclosed.

In the structure of Figures 10 and 11 the bridging and centering portions 18, 19 are supported by a transversely extending brace 29 which is integrally attached to the rim of the head at a point approximately midway between the prongs and is bent across the cavity of the head beneath the base portions 18, 19, as shown in Figure 11. The free end of this brace may be turned up or 40 outward over the edge of the rim as shown at 30.

In the form of the invention shown in Figure 12, the thrust transmitting brace for the prongs is provided by indenting the 45 center of the head into the form of a boss 31 standing beneath and operating as a

support for the abutting inner ends of the prongs. This construction has the advantage of the others described in which a direct thrust transmitting connection is provided from the base of the prongs to the center of the head. 50

What I claim is:

1. A one piece sheet metal fastening having an arched head with prongs having base portions integrally attached at the rim thereof, said base portions extending substantially straight across the concavity of the arch and forming a bridge from which the prongs project and an integral reinforcement between said bridge and the central portion of the arched head. 55

2. The structure of claim 1 in which the reinforcement is in the form of a direct thrust transmitting member cut out of the 60 material of one of the prongs. 65

3. The structure of claim 1 with integral securing means fastening together the base portions of the prongs. 70

4. A one piece sheet metal rivet construction having a cupped head with prongs having base portions integrally attached to the rim of said head, said base portions extending substantially straight across the concavity of the cupped head spaced away 75 from the bottom wall thereof, and means for holding said base portions in said spaced relation to the head. 80

5. A one piece sheet metal rivet construction having a cupped head with prongs having base portions integrally attached to the rim of said head, said base portions extending substantially straight across the concavity of the cupped head spaced away 85 from the bottom wall thereof, and means for holding said base portions in said spaced relation and comprising interengaging portions on the prongs fastening them together. 90

In testimony whereof I affix my signature.

EDWIN B. STIMPSON.
